FASTENING DEVICE

John N. M. Howells, Kittery Point, Maine

Original application October 21, 1944, Serial No. 559,772. Divided and this application January 19, 1946, Serial No. 642,194.

13 Claims. (Cl. 85—10)

1 This invention relates to fastening devices. More particularly the invention pertains to self-retroverting nails.

One of the objects of my invention is to provide a strong nail, preshaped so as to be self-retroverting, and adapted to be driven into material in such preshaped form.

Another object of my invention is to provide a nail of the character described which will revert irrespective of the density of the material into which it is driven.

Another object of the invention is to provide a preformed nail of the character described which is so constructed that it may be readily driven into material without the exercise of special skill.

Other objects of this invention will in part be obvious and in part hereinafter pointed out.

The invention accordingly consists of the features of construction, combinations of elements and arrangements of parts which will be exemplified in the constructions hereinafter described, and of which the scope of application will be indicated in the claims.

The instant application is a division of my co-pending application for Means for applying fastening devices, filed October 21, 1944, as Serial #559,772, and is a continuation-in-part of my application for Fastening devices and means for applying the same, filed April 24, 1942, as Serial No. 440,342.

In the accompanying drawings, in which are shown various possible embodiments of my invention,

Fig. 1 is a sectional view showing a notched nail embodying my invention driven through two wooden boards;

Fig. 2 is a similar view, but with only the point of the nail inserted and a driving tool therefor in operative position;

Fig. 3 is a top plan view of the nail and tool shown in Fig. 2;

Fig. 4 is a front elevational view of the driving tool;

Fig. 5 is a view similar to Fig. 1, showing a nail embodying a modified form of my invention;

Fig. 6 is a view similar to Fig. 2 showing a modified form of tool for driving a smooth shank nail embodying my invention;

Fig. 7 is an enlarged sectional view taken substantially along the line 7—7 of Fig. 6;

Fig. 8 is a view similar to Fig. 2 showing still another modified form of tool and likewise driving a smooth shank nail; and

Figs. 9 and 10 are enlarged sectional views

taken substantially along the line 9—9 and 10—10, respectively, of Fig. 8.

Essentially, a nail embodying my invention has a shank which is curved for substantially its entire length to such an extent that the direction of travel of the tip of the nail, along the arc of the shank from the head to the tip, has a component directly opposite to the direction of travel of the nail head. The tip of the nail is preferably pointed and the head, as is usual in the art, may be provided with a projecting portion which extends laterally beyond the nail shank to expedite pulling the nail out of material.

The nail may be smooth or provided with notches, this depending to some extent upon the type of driving tool employed. This tool may be so constructed that it can successively apply to portions of the nail shank about to enter material a force substantially normal to the surface of said material. Another type of tool in which the driving force is applied to the nail head is shown in my copending application for Machine for driving curved self-retroverting nails, Serial No. 483,594, filed April 19, 1943.

Referring now in detail to the drawings and more particularly to Figs. 1 through 3, I have there shown a self-retroverting nail 10 shaped and constructed in accordance with my invention. Said nail includes a curved shank 12 which is tipped at one end by a driving point 14 and is provided at the other end with a head 16.

The shank 12 is preformed to a shape which it is desired to have the nail maintain during and after driving the nail home into material. Such shape is preferably selected to obtain the best holding effect with the material or combinations of material with which the nail is to be employed. Furthermore, as stated above, this curvature of the shank is such that the direction of travel of the driving point 14, along the curve of the shank from the head to the point, has a component directly opposed to the direction of travel of the nail head 16. With such a construction any force tending to pull apart two pieces held together by the nail imbeds the nail tip more securely.

The nail 10, shown in Figs. 1 through 3, is adapted to be used in wood and has a circularly segmental contour embracing a large arc of almost 180° so that the nail may grip the wood extensively and be held firmly against retraction. When said nail is driven home, its point 14 will revert back almost to the exposed surface of the top board W.

Pursuant to my invention, the curved portion 55 of the shank may embrace an arc of at least

90° to about 180°. The greater the arc embraced by the shank the greater will be the self-retroverting effect obtained, but the greater also will be the difficulty in driving the nail. It will thus be appreciated that it is desirable to have an arc substantially greater than 90°, but substantially less than 180°—a range of from about 110° to 160° providing highly satisfactory results. However, it will be understood that all nails having curved shanks covering an arc greater than 90° and whose tips during driving of the nail travel in a direction having a component directly opposed to the direction of travel of the nail head fall within the scope of my invention.

The cross-sectional contour of the shank 12 may be of a generally circular outline except where the same, as hereinafter explained, is notched. However, said shank may alternatively assume any other desirable or conventional outline, as for example, oval, rectangular or triangular. Also, the nail may, as shown, be of substantially uniform diameter from head to tip, disregarding notches, with an abrupt taper to form a point, or the nail may be tapered all the way from the head to the point or be tapered to the point from any portion of the shank intermediate the head and point without affecting the essential novelty or operation of the nail.

The head of the nail should be such that it overhangs the shank, at least partially, and to this end the head may be longer than the diameter of the shank in one dimension. In order to simplify construction of the driving tool, the head of the nail is preferably no greater than the diameter of the shank at right angles to said dimension. Of course, the head in brad type nails embodying my invention may simply comprise an end of the shank and have no portion projecting laterally beyond the same.

In the form of the invention illustrated in Figs. 1 through 3, I have shown the head 16 specially proportioned and formed to cooperate with a driving tool 18 hereinafter more fully described. For this specific purpose, said head is longer than the diameter of the shank 12 in the plane in which the nail is curved and shorter than said diameter at right angles to said plane.

The inner surface of the point 14 may be formed to the same circular curvature as the shank 12, so that it will guide said shank along the desired path through overlying boards W, W'.

Since the nail is not deformed during insertion, it will retain its full original strength and will be able to firmly hold the two wooden boards, W, W', together. It will also be appreciated that since the point and shank stay in fixed angular relationship and the shank is a circularly segmental arc, the bore pierced through the wood by the point 14 is never crushed or mutilated by the shank, and the full length of this bore and the entire peripheral area thereof will thus be available to frictionally engage the nail shank.

The diameter and length of the nail in inches may be varied as desired, and the selection of any particular diameter and length will depend upon the use to which the nail is to be put.

Referring now to Figs. 2 through 4, I have there illustrated an apparatus which will give satisfactory results in driving a nail embodying my invention. Said apparatus comprises a driving tool 18 composed of a metal post 20 having a hardened upper end. The lower end of the post is undercut at 22 for a purpose which will soon be apparent. Rivets 24 permanently secure a gripping member 26 of resilient material,

such as a strip of spring steel, to the lower end of the post. Portions 28 of the gripping member 26 are bent to lie snugly against the sides of the post and offset portions 30 at the end of the portions 28 partially overlie and snugly fit against the front of the post. From the offset portions 30, the ends of the member 26 extend away from the post in two substantially parallel walls 32 which are provided with oppositely indented registered arcuate grooves 34 and 36 of the same general configuration as the nail shank 12. Said grooves 34 and 36, which together provide a passageway P for the nail shank 12, are so arranged relatively to the post 20 that when a nail 10 is introduced into said passageway, the shank of the nail will traverse the undercut 22 of the post.

The passageway P is slightly narrower than the diameter of the smallest shank to be employed with the tool 18, so that when a nail is introduced into said passageway, it will be lightly frictionally gripped between the two walls 32.

The shank 12 of the nail 10 in this form of my invention is provided throughout its length with a plurality of notches 38, each of which has a short step 40 substantially parallel to the radius of curvature of the shank. The face 42 of each notch is approximately perpendicular to its associated step 40, or to the step 40 of the immediately preceding notch in the direction toward the nail point 14.

The toe 44 of the post 20 at the bottom of the undercut 22 is hardened and is so disposed relative to the passageway P that when the point 14 of a nail 10 is pushed sufficiently far through said passageway, said toe 44 will lie in the foremost notch 38.

If desired, the toe 44 may be so fashioned that its under surface 46 lies flatly on the steps 40 of the notches, and its forward surface 48 lies flat against the faces 42 thereof.

After the nail has been introduced into said passageway and is lightly held by the walls 32, the point 14 will project beyond the bottom of the tool 18. Said point is placed against the material into which the nail is to be driven, the post is vertically disposed, and a hammer blow is applied to its upper end. The driving impulse which is imparted will be transmitted from the toe 44 to the first step 40 of the shank 12, causing the nail to move until said step lies flush against the surface of the material. While the post 20 is moving downwardly, it will remain vertical and, depending upon the formation of the toe 44, may shift laterally slightly away from the nail shank. The relative angular position of the nail shank and post will, therefore, be altered. But this relative movement is taken up by spring action of the walls 32. The tool 18 is now disengaged from the first notch 40 and moved to the second notch, this position being shown in Fig. 2. Thereupon, another driving impulse is applied. This procedure is repeated until the step of the last notch lies flush against the surface of the material. The head of the nail may now be directly driven into the wood by the hammer.

In Fig. 5 I have shown a nail 50 embodying a modified form of my invention, the same being so constructed that it will provide a greater clinching effect than the semi-circular nail 10 above described. In said nail 50 the radius of curvature of the shank 52 varies from the head 54 to the point 56, being least adjacent the head and greatest adjacent the point. Such construction enables the nail to traverse a greater span.

Nails of this type are particularly useful with wall board B. Where a preformed nail is driven through such relatively soft material, the inner surface of the point 56 need not have a curvature which matches that of the shank 52, since said shank will be strong enough to resist any bending stress imposed during insertion.

While in the foregoing embodiments of my invention I have described the curved shank of the self-retroverting nail as provided with notches, it will be understood readily that the shank may be smooth and free from notches or projections.

In Fig. 6 I have shown such a self-retroverting nail 60 whose shank 62 comprises a segment of a circle covering an arc of approximately 150° from its pointed tip 64 to its head 66.

Said nail may be driven into material by a tool 68 adapted to drive a nail having either a notched or smooth shank. The tool 68 includes a metal driving post 70 having a hardened upper end. The lower end of the tool is enlarged to form a driving head 72 containing a driving clamp 74 specially constructed to engage and disengage with any portion of the curved nail shank intermediate its two ends so that driving impulses applied to the upper end of the post will be transmitted therethrough to the nail shank to force the same into the boards W, W'.

Said driving clamp includes two driving shoes 76, 78 slidably received in horizontal and vertical slots 80, 82 provided in the driving head 72. One driving shoe, for example, the left-hand shoe 76, has a convexly curved and grooved right-hand edge 84 which negatively matches the external configuration of the underside of the nail shank 62. Said curved edge is adapted to engage about 90° of the transverse contour of said shank. The right-hand shoe 78 has a convexly curved and grooved left-hand edge 86 which negatively matches the external configuration of the upper side of the curved nail shank. This groove also covers about 90° of the transverse contour of said shank so that the two sides or flanks of the shank are left free when the shoes, 76, 78 engage said shank. Each shoe has an inclined cam slot 88, 90 formed therein. These slots extend in a generally upward direction and converge at a slight angle towards each other, the angle shown in Fig. 6 being exaggerated for purposes of illustration.

A pair of hard, tough pins 92, 94 whose opposite ends are secured in the lateral walls of the driving head 72 bridge the horizontal slot 80, each pin being received in one of the shoe slots 88, 90. The diameter of the pins is slightly less than the width of the slots, this also being exaggerated for purposes of illustration in Figs. 6 and 7. Springs 96, 98 resiliently bias the shoes 76, 78 upwardly. This causes the grooved and curved edges 84, 86 to be urged towards each other.

The pins 92, 94 are so spaced apart that when the springs urge the shoes upwardly as far as they can go, the bottoms of the slots abutting the pins, the distance between the grooved and curved side walls 84, 86 will be less than the diameter of the shank of a nail to be driven. Thus, when a nail shank is introduced between the shoes, it will be bound lightly in the driving tool. This binding action, however, is not sufficient to prevent a nail shank from being forced manually, with ease, through the passageway defined by the shoe edges 84, 86.

The head 72 is provided with entrance and exit apertures 100, 102 forming a continuation of the said passageway defined by the shoes and aiding to hold and position the shank of the nail.

When a driving impulse is applied to the upper end of the tool post 70, the pins 92, 94 first move downwardly relative to the shoes 76, 78 which at such time lightly frictionally engage the nail shank. Said initial relative downward movement, which is very slight, causes the shoes to firmly grip the nail shank, whereupon the shoes transmit the driving impulse. Such impulse will force the point of the nail in the board W or cause said point to travel further through the boards W, W'. The tool is now backed off, that is, grasped by the tool post and pulled back along the shank. Initially, this movement of the tool moves the pins 92, 94 upwardly relative to the shoes 76, 78 which drag along the shank. Such upward movement will relieve the pressure of the shoes against the shank and permit the tool then to be moved readily to a portion of the shank further from the material into which the nail is being driven.

The head 68 of the nail is of such configuration that its projecting portions will pass between the edges 84, 86 of the shoes without contacting same, due to the fact that said edges are spaced.

In addition, the driving head has laterally disposed grooves 104 to freely pass said head portions. When the nail has been driven in to such an extent that the head leaves the exit aperture 102, the tool 68 is put to one side and the head of the nail directly driven into the wood with the hammer.

In Figs. 8 and 9, I have shown still another modified form of tool 108 for driving a nail 60 having a smooth shank. Said tool includes a metal driving post 110 having a hardened upper end. The lower end of the post is provided with an undercut notch 112 similar to the undercut 22 of the tool 18 shown in Figs. 2-4. A spur 114 extends into the bottom of said notch. Said spur 114 has a roughly V-shaped transverse (horizontal) configuration (Fig. 10) and is relieved at its back side 116 to provide a sharp V-shaped driving edge 117. Rivets 118 permanently secure a gripping member 120 of resilient material, such as a strip of strong steel, to the lower end of the post. Portions 122 of the gripping member are bent to lie snugly against the sides of the post. The ends of these portions 122 extend away from the post and are provided with oppositely indented registered arcuate grooves 124, 126 of the same configuration as the flanks of the nail shank. Said grooves together define a holding passageway for the nail shank 62 leading past the tip of the sharp V-shaped driving edge 117.

When an impact is applied to the top of the post 110, the driving edge 117 will dig into the nail shank and cause the nail to move arcuately into the wood boards W, W' until said edge reaches the upper board W.

It may be mentioned that the edge 117 is able to dig into the nail shank because the resilient arms 122 spread during driving, allowing the nail shank to leave the holding passageway and to lie flush against the notch 112.

After the nail has been driven to such an extent that the edge 114 is close to the board W, the tool is shifted back along the nail to dispose the edge 117 adjacent another portion of the shank closer to the head, and the driving operation is repeated.

The above described tools are fully shown, described and claimed in my copending application, Serial No. 559,772.

It will thus be seen that I have provided nails which achieve the several objects of my invention,

and which are well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A nail comprising a head, a tip and an elongated preformed longitudinally curved shank intermediate said tip and said head, the curvature of the shank being such that the direction of travel of said tip along the curve of the shank from the head to the tip has a component directly opposed to the direction of travel of said head.

2. A nail comprising a head, a tip and an elongated preformed longitudinally curved shank intermediate said tip and said head and embracing an arc of from at least 90° to about 180°.

3. A nail comprising a head, a tip and an elongated preformed longitudinally curved shank intermediate said tip and said head, the curvature of the shank being such that the direction of travel of said tip along the curve of the shank from the head to the tip has a component directly opposed to the direction of travel of said head and so that the shank covers an arc of greater than 90°.

4. A nail comprising a head, a tip and an elongated preformed longitudinally curved shank intermediate said tip and said head, the curvature of the shank being such that the direction of travel of said tip along the curve of the shank from the head to the tip has a component directly opposed to the direction of travel of said head and

so that the shank covers an arc of no more than 180°.

5. A nail as set forth in claim 4 wherein the curvature of the shank is uniform.

6. A nail as set forth in claim 4 wherein the shank is notched whereby a driving tool may be employed for driving the nail.

10 7. A nail as set forth in claim 4 wherein the shank is provided with notches along the outer-side of the curve whereby a driving tool may be employed for driving the nail.

15 8. A nail as set forth in claim 4 wherein the shank is provided with notches at uniform intervals along the outer-side of the curve whereby a driving tool may be employed for driving the nail.

9. A nail as set forth in claim 4 wherein a head is provided which is larger than the shank of the nail in one dimension at right angles to said shank and smaller than the shank in another dimension at right angles to said shank and said first dimension.

20 10. A nail as set forth in claim 4 wherein the curvature of the shank varies from the head to the point, being sharpest adjacent the head and flattest adjacent the point.

11. A nail comprising a head, a tip and an elongated preformed longitudinally curved shank intermediate said tip and said head, the curvature of said shank being substantially semi-circular.

30 12. A nail comprising a head, a tip and an elongated preformed arcuately curved shank intermediate said tip and said head, the curvature of said shank extending longitudinally thereof substantially 180°.

35 13. A nail as set forth in claim 4 wherein the shank is smooth.

JOHN N. M. HOWELLS.
